UNITED STATES PATENT OFFICE.

DE WANE B. SMITH, OF DEERFIELD, NEW YORK.

DESIGN FOR A SPRAYER-BODY.

SPECIFICATION forming part of Design No. 32,398, dated March 27, 1900.

Application filed December 22, 1899. Serial No. 741,341. Term of patent 7 years

To all whom it may concern:

Be it known that I, DE WANE B. SMITH, a citizen of the United States, and a resident of Deerfield, county of Oneida, and State of New York, have invented and produced a new, useful, and original Design for a Sprayer-Body, of which the following is a specification, reference being had to the accompanying drawing, forming part thereof.

10 The drawing shows a perspective view of a sprayer-body of the form or configuration produced by me.

The leading and material features of the design or form consist of the large cylinder 1, the parallel small cylinder 2 on the side of

the large cylinder, the loop or handle 3, and the projection 4, all relatively arranged substantially as shown in the drawing.

Having described my invention, what I claim as new, and desire to secure by Letters 20 Patent, is—

The design for a sprayer-body substantially as shown and described.

In witness whereof I have hereunto set my hand, in the presence of two witnesses, this 25 9th day of December, 1899.

DE WANE B. SMITH.

Witnesses:

JULIA DRISCOLL,
E. WILLARD JONES.
